FOREIGN PATENT DOCUMENTS

CA 185240 2/2020

Primary Examiner — Clare Ann Gannon

(74) Attorney, Agent, or Firm — McCormick, Paulding & Huber, PLLC

CLAIM

The ornamental design for a valence substantially as shown and described.

DESCRIPTION

FIG. 1 is a front perspective view of the first variant of the article;

FIG. 2 is a rear perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of the article that form no part of the claimed design. The break lines and curly brackets shown in the figures illustrate breaks in the length of the article that form no part of the claimed design. The appearance of any portion of the article between the break lines forms no part of the claimed design.

1 Claim, 8 Drawing Sheets
